B. KUMAGAI.
PENCIL SHARPENER.
APPLICATION FILED JULY 23, 1917.

1,296,971.

Patented Mar. 11, 1919.

UNITED STATES PATENT OFFICE.

BUNTARO KUMAGAI, OF SEATTLE, WASHINGTON.

PENCIL-SHARPENER.

1,296,971.

Specification of Letters Patent. Patented Mar. 11, 1919.

Application filed July 23, 1917. Serial No. 182,260.

To all whom it may concern:

Be it known that I, BUNTARO KUMAGAI, a subject of the Emperor of Japan, residing at Seattle, in the county of King and State 5 of Washington, have invented certain new and useful Improvements in Pencil-Sharpener, of which the following is a specification.

My invention relates to pencil sharpeners and the like, and has for its primary object 10 the provision of a device of a simplified and economical construction wherein the abrading knife is easily removed and replaced.

With the above and other objects in view, 15 to be referred to as my description progresses, my invention resides in the features of construction, arrangements, and combination of parts hereinafter described and pointed out in the appended claims.

Referring to the accompanying drawings, 20 wherein like reference numerals designate like parts throughout the several views, Figure 1 is a front elevation of a memorandum pad holder embodying the principal 25 features of my invention, parts being broken away. Fig. 2 is a top plan view thereof with portions broken away. Fig. 3 is a fragmentary rear elevation thereof showing the 30 knife element in a reverse position from that shown in Fig. 2. Fig. 4 is an end elevation thereof showing a pad in position. Fig. 5 is a transverse section taken on line 35 5-5 of Fig. 1. Fig. 6 is a perspective view of one form of a knife element employed in my device. Fig. 7 is a vertical elevation 40 of a pencil point shield embodying the principal features of my invention, parts being broken away. Fig. 8 is a side elevation of the same. Fig. 9 is a horizontal section taken on line 9-9 of Fig. 7.

Referring to the drawing by numerals of reference, 1 indicates the hollow conical body of the pencil sharpener 10 which may be integral or otherwise rigidly secured, as 45 by solder, to the base and back section of a memorandum pad holder 2 preferably at or near one end thereof.

This memorandum pad holder 2 being of a well-known type with the exception of a 50 few minor structural changes, has the usual base 20 provided along its forward edge with teeth 20¹ and having an integral back section 21 to which a jaw member 22 is pivoted by a pintle 23. Said jaw member 22 55 overlies base 20 and is yieldingly pressed toward said base by suitable springs 24 and

having on its forward or free edge, teeth 22¹ arranged in opposing relation to teeth 20¹ of base 20 and adapted to firmly hold a pad 25, as shown in Fig. 4. 60

In the present construction, I have shown the hollow conical body 1 integral with base 20 and back section 21 and have provided at one end of said back section a longitudinal slot 3, the latter communicating with 65 the interior of the conical body 1 and the exterior face of the back section 21 thereby permitting the discharge of the cuttings when a pencil is being sharpened.

Guideways 40 are also provided in said 70 back section for the reception of a knife element 4, said guideways being in vertical alinement with slot 3 and below same. The knife 4 is preferably U-shaped and has four cutting edges 42, 42¹ thereby furnishing the 75 maximum efficiency and greatly increasing the utility of my device.

When the knife 4 is in its normal position, 80 as shown in Figs. 1, 2, 4 and 5, cutting edge 42¹ of said knife is adapted to be in the path of the pencil, to be sharpened, while the remaining cutting edges are protected in the guideways 40 and lip 43, the latter being an integral extension of back section 21. When, 85 however, the knife element 4 is in the position shown in Fig. 3, in order to facilitate the insertion of the knife in guideways 40 I provide a longitudinal depression 30 in the back section 21, said depression extending from the slot 3 to a point near the center of 90 the back section, said depression being of ample height, length and depth to facilitate the insertion of said knife.

A further feature of my device is the enlarged opening 11 at the smaller end of the 95 hollow conical body 1 to thereby facilitate the discharge of refuse such as shavings or broken points, the latter being pushed through the smaller end instead of being extracted through the large end, as is now 100 done.

In the form shown in Figs. 7, 8 and 9, I have shown my device as applied to a shield 5, as is commonly used to protect pencil points while same are being carried in the 105 pocket.

This shield 5 has a conical body portion, 110 as 50, and a straight portion, as 51, the latter having threads or corrugations 52 to feed and guide the pencil 7 while being sharpened, and also to hold the pencil when the device is being used as a shield, thereby pre-

venting the accidental removal of said shield, as sometimes occurs. A spring clip 53 is fastened to the shield as by rivets 53¹, to thereby furnish means to secure the same to the wall 5 of the pocket.

A guide flange 54 is integrally connected by a rib 55 to the conical body portion 50, thereby furnishing guideways 56 for a knife 6 said knife being similar in shape to the 10 knife 4, as hereinabove described, with the exception that the knife 6 is provided with longitudinal central slots 60 in its legs thereof, the object of said slots being to allow the knife to be disposed astride of rib 55 irrespective of the direction in which the knife 15 is inserted, as will be clearly understood.

To facilitate the insertion of the knife 6 in an upward direction, at the lower end of guideways 56 the straight portion 51 of 20 shield 5 is cut out at 51¹.

Copies of this patent may be obtained for five cents each, by addressing the "Commissioner of Patents, Washington, D. C."

Having thus described my invention, what I claim as new and desire to secure by Letters-Patent of the United States, is—

1. In an article of manufacture, a U-shaped knife having cutting edges on the opposite 25 sides of each of its two arms.

2. In a pencil sharpener, in combination, a casing, a flange on said casing having guideways disposed on each face thereof, a U-shaped cutting knife adapted to be positioned in said guideways, and means carried by said casing to guide the article to be sharpened. 30

In testimony whereof I affix my signature in presence of two witnesses.

BUNTARO KUMAGAI.
